UNITED STATES PATENT OFFICE.

RICHARD R. MEAD, OF BROOKLYN, NEW YORK, ASSIGNOR TO MERGENTHALER LINOTYPE COMPANY, A CORPORATION OF NEW YORK.

SPACE-BAND-TRANSFER MEANS FOR TYPOGRAPHICAL MACHINES.

Application filed July 8, 1927. Serial No. 204,237.

This invention relates to typographical machines, such as linotype machines of the general organization represented in Letters Patent of the United States, No. 436,532, to 5 O. Mergenthaler, wherein circulating matrices are released from a magazine in the order in which their characters are to appear in print and then assembled in line together with spacers or spacebands, the composed line transferred to the face of a mold, the mold filled with molten metal to form a 10 slug or linotype against the matrices which produce the type characters thereon, and the matrices and spacers thereafter elevated and 15 returned through distributing mechanism to the magazines from which they started.

More particularly, it relates to the transfer means employed for restoring the spacers, after their separation from the matrices in the so-called upper transfer channel, to their magazine or place of storage. The 20 regular linotype machines are ordinarily constructed for the handling of composed lines not exceeding 30 ems in length, but to 25 meet the demand created by certain classes of editorial and book work, special machines have recently been built which are capable of handling lines as high as 42 ems in length.

In these larger machines, the upper transfer 30 channel is about two inches longer than the corresponding part in the smaller regular machines, and the stroke of the spacer delivery pawl associated therewith is increased accordingly. Ordinarily, this spacer delivery pawl is pivoted on a fixed axis to the upper 35 end of a cam-controlled operating lever, and as thus supported, the pawl is caused to assume an inclined position in relation to the horizontal rails of the transfer channel.

40 during part of its active stroke. Although thoroughly practical in the standard machines, such arrangement has been found to be unsuitable for the 42 em machines and this primarily because of the greater number 45 of spacers which have to be handled by the delivery pawl when the composed lines range from 30 to 42 ems in length. Thus, when such a large number of the commercial wedge-shaped spacers are drawn together at 50 their relatively thin upper ends, they are collected in a fan-like condition and the first spacer of the group will stand inclined in the same general direction as that of the

delivery pawl. As a result of this condition, and also because of the swinging tendency of the spacers, the delivery pawl frequently loses its slight purchase on the spacers and fails to deliver them into the storage magazine. Moreover, the pawl, in dragging over the tops of the freed spacers, is likely to 55 twist them in the transfer channel or dislodge them completely from their supporting rails, so that at the next operation of the pawl the spacers may be seriously damaged or many of them spilled into the machine.

The present invention is intended to obviate these and other difficulties and contemplates certain improvements whereby the delivery pawl will maintain its purchase 60 on the spacers irrespective of the number 65 composed in a single line. To this end, specifically, the pawl is loosely connected to the upper end of its operating lever and is 70 acted upon by a spring in such manner that it is held resiliently in a horizontal position at all times during its operation. The arrangement also permits the pawl to yield bodily upwards with relation to the operating lever, which feature is advantageous in 75 permitting the pawl to clear the second elevator bar during its idle movement.

In the accompanying drawings, the invention is shown in preferred form and by way of example, and as applied to a linotype machine, but many changes and variations 80 may be made therein and in its mode of application, which will still be comprised within its spirit. Generally speaking, the invention is not limited to any specific form or embodiment, except in so far as such limitations are specified in the claims.

Referring to the drawings:

Fig. 1 is a front elevation of a portion of a linotype machine equipped with the present improvement;

Fig. 2 is a similar view showing certain of the movable parts in another position;

Fig. 3 is an elevation, on an enlarged scale, of the spacer delivery pawl and connected parts in operative relation to the upper 100 transfer channel;

Fig. 4 is a vertical section taken on line 4—4 of Fig. 3;

Fig. 5 is a horizontal section taken on line 5—5 of Fig. 3; and

spacer delivery pawl and operating lever as heretofore employed in linotype machines of standard construction.

Referring to Fig. 1, the matrices x and 5 spacers y are delivered one by one to the assembler A, wherein they are composed side by side in line in the usual way. The assembler is then elevated and the composed 10 line transferred through the intermediate channel B into the first elevator C, which immediately descends to present the line in casting position. After the slug has been cast, the composed line is lifted by the first elevator to the dotted-line position 1 and is 15 then shifted horizontally into the upper transfer channel D to the dotted-line position 2, the matrices during transfer engaging the ribbed second elevator bar E, and the spacers being suspended by their projecting ears y^1 on the horizontal rails D^1 of the channel D (see Fig. 4). The second elevator is now raised to transport the matrices to the distributing level, and the spacers are left behind in the upper transfer channel 20 to be subsequently delivered along the supporting rails D^1 to their storage magazine Y. The foregoing parts and their mode of operation are old and well known and require no further description.

30 As before stated, the present invention contemplates certain improvements in the spacer delivery devices which are particularly applicable to the special 42 em machine before referred to. These devices usually comprise a pair of vertically-disposed rocking levers F and G, the lever F being fast to a rock shaft F^1 which is operated by a cam, not shown, and the lever G being pivoted at its lower end on a stud G^1 mounted 35 in the main frame of the machine. The levers F and G are connected together so that the movement of one causes a corresponding movement of the other, being arranged to cooperate in shifting the matrices and spacers of a composed line in the manner required. A turnbuckle H constitutes the connecting link, as shown in Fig. 1, and is arranged between an arm F^2 depending from the hub of the lever F and a lug formed on 40 the lever G at a predetermined distance above its pivotal axis G^1 . At its upper end, the lever F is connected by a link F^3 to the well-known transfer slide F^4 , mounted in suitable guideways formed in the front plate 45 J and provided with a finger F^5 adapted to engage the matrix line as the lever F is rocked to the right. The lever G, on the other hand, is provided at its upper end with a pawl or hook G^2 which is arranged 50 in operative relation to the channel D and is intended to cooperate with spacers suspended therein in effecting their delivery to the magazine Y. The matrices and spacers must first be separated before the latter 55 operation can take place, and consequently,

two successive operations of the levers F and G are required during each machine cycle. By the first operation, the line is shifted by the finger F^5 from position 1 to position 2 to engage the matrices with the 70 second elevator bar E, the hook G^2 at such times occupying the relatively neutral position indicated by the dotted lines in Fig. 1. The finger and hook then recede in opposite directions far enough to clear the elevator 75 and thus allow the latter to ascend with the matrices to the distributor. The second operation causes the finger and hook to be brought into closer relation, as shown in Fig. 2, the finger this time serving to push 80 the spacers together and to support them facewise as the hook rides over them and drops in behind their projecting ears y^1 . As the levers F and G are restored to their normal position, the hook G^2 draws the 85 spacers along the horizontal rails D^1 and deposits them in the magazine Y (Fig. 1).

According to the present invention, the hook G^2 , which has heretofore been pivoted fixedly to the upper end of the lever G (see 90 Fig. 6), is loosely connected thereto so that it may travel in a horizontal position upon the transfer channel and thus be capable of maintaining its purchase on the upper ends of the spacers during its active stroke. As 95 best shown in Figs. 3 and 5, the hook is recessed or bifurcated at its rear end to receive the lower portion of a supporting block G^3 , to which it is directly connected by a cross pivot pin G^4 . This pin is fastened in 100 the block G^3 and engages elongated slots G^5 formed in the upstanding side portions G^6 of the hook G^2 . In other respects, the hook is substantially the same as the old type shown in Fig. 6, being formed with a beveled nose portion G^7 , which enables it to ride over the tops of the spacers on its idle stroke, and with shoulders G^8 , G^9 , between which the spacers are confined preparatory to their delivery when the parts reach the position 105 shown in Fig. 2. In the present instance, the hook G^2 is provided at its opposite ends with guide pins G^{10} , which are adapted to track upon the top of the transfer channel D as the spacer lever is reciprocated and 110 thus sustain the hook in a horizontal position thereon. A compression spring G^{11} , arranged above the hook between a forward extension G^{12} of the block G^3 and a collar formed on the lower end of a rod G^{13} , acts 115 through the latter to hold the hook G^2 , under the required tension, resiliently down upon the upper edge of the channel D. The rod G^{13} is guided at the top in the extension G^{12} and, at the bottom, seats in an anti-friction pocket formed in the hook G^2 . The block G^3 is secured to the upper end of the lever G by a clamping screw G^{14} and is capable of a slight lateral adjustment in order 120 that the hook may be properly set or cen- 125 130

tered, at the time of assembling, in operative relation to the channel D. Such adjustment is amply provided for (see Fig. 5) by making the screw hole G¹⁵ somewhat larger than the shank of the clamping screw.

It will now be seen that the spacer delivery hook G² will always be maintained resiliently in the desired position on the channel D during the reciprocation of the lever G notwithstanding the arcuate or curved path traversed by the block G³ about the pivotal axis G¹, the change in the position of the pivot pin G⁴ relatively to the top of the channel at such times being fully compensated for by the slots G⁵. Tilting of the hook and the resultant danger of losing its purchase on the spacers are thus greatly minimized, if not entirely eliminated. Moreover, and inasmuch as the hook G² under the present arrangement is capable of yielding bodily in relation to the top of the transfer channel D, it will ride up and over the end of the second elevator bar plate E¹ to assume a position of rest thereupon as the "first operation" of the transfer levers F and G is completed, see dotted lines in Fig. 1. If the hook were mounted in the usual way, the pivotal axis thereof would either cause interference with the bar plate E¹ or be brought so close to it that the nose of the hook would be forced upwardly at an awkward angle and soon result in setting or breaking the compression spring. These and other advantages will be readily appreciated by those skilled in the art.

It is obvious that the particular construction or arrangement shown and described may be variously modified without departure from the scope of the invention, it being possible to connect the spacer delivery pawl to its operating lever in diverse ways and still enable it to function in the required manner.

Having thus described my invention, its construction and mode of operation, what I claim and desire to secure by Letters Patent of the United States is as follows:

1. In a linotype machine equipped with spacers, the combination with the spacer magazine and the upper transfer channel communicating therewith, of a hook or pawl for delivering the spacers from the channel to the magazine, a pivoted operating lever connected directly to the hook, and intermediate connecting means whereby the hook is maintained resiliently in a horizontal position upon the channel during its operation.

2. In a linotype machine equipped with spacers, the combination with the spacer magazine and the upper transfer channel communicating therewith, of a hook or pawl for delivering the spacers from the channel to the magazine, a reciprocating support movable in a curved path for operating the hook, and means connecting the hook di-

rectly to the support whereby the former is maintained resiliently in a horizontal position upon the channel during its operation.

3. In a linotype machine equipped with spacers, the combination of the upper transfer channel, a vertically disposed pivoted operating lever, a hook or pawl arranged to cooperate with spacers suspended in said channel, and means connecting the hook directly to the upper end of the lever whereby the hook is capable of yielding bodily and is allowed to travel in a horizontal position upon said channel as the lever is reciprocated.

4. In a linotype machine equipped with spacers, the combination of the upper transfer channel, a vertically disposed pivoted operating lever, a hook or pawl pivoted on a shiftable axis directly to the upper end of said lever for bodily movement in relation thereto, and a spring for maintaining the hook resiliently upon the transfer channel as the lever is reciprocated.

5. In a linotype machine equipped with spacers, the combination with the spacer magazine and the upper transfer channel communicating therewith, of a hook or pawl for delivering the spacers from the channel to the magazine, a vertically disposed reciprocating lever for operating the hook, a supporting block for the hook secured to the upper end of the lever, and a shiftable pivotal connection between the block and the hook to allow the latter to yield bodily and to travel in a horizontal position during its operation.

6. In a linotype machine equipped with spacers, the combination of the upper transfer channel, a vertically disposed pivoted operating lever, a support block carried by the upper end of the lever, a hook or pawl pivotally connected on a shiftable axis to the block and arranged to cooperate with spacers suspended in said channel, and means for adjusting the block laterally to set the pawl in operative relation to the channel.

7. In a linotype machine equipped with spacers, the combination of the upper transfer channel, a vertically disposed pivoted operating lever, a support adjustably clamped to the upper end of the lever, a hook or pawl pivotally connected on a shiftable axis to the block and arranged to cooperate with spacers suspended in said channel, and a spring interposed between the block and hook for holding the latter resiliently in horizontal position during its spacer delivery movement.

8. In a linotype machine equipped with spacers, the combination of the upper transfer channel, a vertically disposed pivoted operating lever, a hook or pawl pivotally connected on a shiftable axis to the upper end of said lever and arranged to cooperate with spacers suspended in said channel, and

means for sustaining the hook in horizontal position upon the channel as the lever is reciprocated.

9. In a linotype machine equipped with 5 spacers, the combination of the upper transfer channel, a vertically disposed pivoted operating lever, a supporting block carried by the upper end of said lever, a hook or pawl pivotally connected on a shiftable axis 10 to the block, a pair of pins projecting laterally from the hook near its opposite ends for sustaining it in a horizontal position upon the channel, and a spring interposed between the block and the hook for holding 15 the latter resiliently in such horizontal position as the lever is reciprocated.

10. In a linotype machine equipped with spacers, the combination of the upper transfer channel, a vertically disposed pivoted 20 operating lever, a supporting block carried by the upper end of said lever, a hook or pawl connected by a pin and slot to the block, means for adjusting the block laterally to set the hook in operative relation to 25 said channel, means for sustaining the hook in a horizontal position upon the channel, and a spring for holding the hook resiliently in such horizontal position as the lever is reciprocated.

30 11. In a linotype machine equipped with

spacers, the combination with the spacer magazine, the upper transfer channel communicating therewith, and the second elevator bar adapted to be lowered into the transfer channel, of a hook or pawl for delivering the spacers from the transfer channel to the magazine, a pivoted operating lever connected directly to the hook, and intermediate means whereby the hook is permitted to mount the second elevator bar on 35 its inactive stroke and to be maintained resiliently in a horizontal position upon the transfer channel during its active stroke.

12. In a linotype machine equipped with spacers, the combination with the spacer 40 magazine, the upper transfer channel communicating therewith, and the second elevator bar adapted to be lowered into the transfer channel, a vertically disposed pivoted operating lever, and a spring actuated 45 hook or pawl pivoted on a shiftable axis directly to the upper end of said lever, whereby the hook on the inactive stroke of the lever may mount the second elevator bar and on the active stroke of said lever may slide 50 horizontally upon the transfer channel in delivering the spacers to the magazine.

In testimony whereof, I have affixed my signature hereto.

RICHARD R. MEAD.
